DESIGN FOR A TABLE

Lurelle Guild, New York, N. Y., and Carlton G. Towne, Pittsburgh, Pa., assignors to The Aluminum Cooking Utensil Company, New Kensington, Pa., a corporation of Pennsylvania.

Application July 26, 1947, Serial No. 140,542

Term of patent 14 years

(Cl. D33—14)

To all whom it may concern:

Be it known that we, Lurelle Guild and Carlton G. Towne, citizens of the United States, residing, respectively, at New York, in the county of New York and State of New York, and at Pittsburgh, in the county of Allegheny and State of Pennsylvania, have invented a new, original, and ornamental Design for a Table, of which the following is a specification, reference being had to the accompanying drawing, forming a part thereof.

Fig. 1 is a view in perspective of a table embodying our new design;

Fig. 2 is a side elevation of the table of Fig. 1;

Fig. 3 is an end elevation of the table of Fig. 1.

The dominant feature of our design resides in the portion of the table shown in full lines.

Our design for a table is characterized by an arcuate skirt member disposed at each of the narrow ends of the table.

We claim:

The ornamental design for a table, substantially as shown and described.

LURELLE GUILD.
CARLTON G. TOWNE.
